Specification of Letters Patent.

Patented Aug. 19, 1913.

Application filed January 3, 1913. Serial No. 740,006.

To all whom it may concern:

Be it known that I, ARTHUR STEINBRECKER, a subject of the King of Great Britain, residing at Calgary, in the Province of Alberta and Dominion of Canada, have invented new and useful Improvements in Excavating and Dredging Machines, of which the following is a specification.

This invention relates to excavating and dredging machines, and it has for its object to provide a machine of the type known as a dredging dipper which shall be simple, inexpensive, easily operated and efficient in operation.

With these and other ends in view which will readily appear as the nature of the invention is better understood, the same consists in the improved construction and novel arrangement and combination of parts which will be hereinafter fully described and particularly pointed out in the claims.

In the accompanying drawings has been illustrated a simple and preferred form of the invention, it being, however, understood that no limitation is necessarily made to the precise structural details therein exhibited, but that changes, alterations and modifications within the scope of the claims may be resorted to when desired.

In the drawings.—Figure 1 is a view in elevation of the machine showing the same in dredging or excavating position. Fig. 2 is a vertical sectional view taken on the line 2—2 in Fig. 1. Fig. 3 is a top plan view. Fig. 4 is a view in elevation, showing the dipper in discharging position. Fig. 5 is a sectional detail view taken on the line 5—5 in Fig. 2.

Corresponding parts in the several figures are denoted by like characters of reference.

The improved apparatus has been shown as mounted on a portable support which may be in the nature of a float, a portion of which is shown at 1, although the apparatus may be erected on the platform of a flat car or any other suitable portable structure. The apparatus includes a mast A which, as shown, consists of a ladder structure, including side members 2, 2 and steps 3. This mast is preferably supported pivotally so as to be capable of rotating about an approximately vertical axis. To this end the mast may be provided at its lower end with a pivot member 4 engaging a socket in the support 1. A pivot member 5 at the upper

end of the mast is provided to engage a cap plate 6 from which guy members or stay members, such as cables 7, extend to suitable anchoring devices.

8 designates a chute or trough which is provided on the underside thereof with transverse cleats 9. This chute or trough may be supported on any one of the steps 3 of the mast, and such step may be engaged between any two of the cleats 9, thereby supporting the chute against longitudinal movement. A second chute 10 is arranged to slide longitudinally of the chute 8 with which it is suitably connected, as by means of flanges 11 formed at the upper edges of the side members of the chute 8; fastening means of any well known description may also be employed for the purpose of assembling the chutes 8 and 11 together in adjusted position, but such fastening means have not been specifically shown. The chute 10 is provided at what will be regarded as its front end with forwardly extending converging arms 12 supporting at their front ends a pivot member 13 on which the dipper or dredging bucket B is hingedly supported. Said dipper or dredging member consists of a chute or trough 14 having at one end thereof a scoop 15. The trough 14 is made of such dimensions that when tilted in the direction of the slideable chute 10 it will engage the front end of the latter so as to discharge therein. The trough 14 is also provided with brackets 16 supporting an arm 17 that extends longitudinally from the trough.

Suitably mounted on the support 1 is a hoisting apparatus including winding drums 18 and 19 which may be suitably driven in any direction by power derived from a donkey engine 20 or from a motor of any description, the transmission means including reversing gearing which is conventionally indicated at 21, but which, being well known, does not require to be described in detail. One of the drums, 18, supports a flexible element 22, an intermediate portion of which is wound on the drum so as to be in frictional engagement therewith, while the two ends of said flexible element are connected, respectively, with the scoop 15, at 23, and with the arm 17, at 24, the parts of said flexible element being guided over guide members such as pulleys, one of which, 25, is supported on the movable or slideable chute 10 by means of a bracket mem-

ber 28, while another guide pulley 27 is supported on the mast 8. The outer or front end of the slidable chute 10 is supported in a stirrup 28 which is connected with the winding drum 19 by a flexible element 29 which is guided over a pulley 30 supported at or near the top of the mast.

From the foregoing description taken in connection with the drawings hereto annexed, it will be seen that by unwinding the flexible hoisting element or cable 29 from the drum 19, the front end of the slidable chute 10 carrying the dipper B will be lowered. The dipper may be tilted by operating the drum 18 so as to cause it to engage the material to be excavated and to bite into the same. By manipulating the drums, the chute 10 may now be elevated so as to cause the dipper to gather a load of material, and the dipper may then be tilted to the discharging position shown in Fig. 4 of the drawings, thus causing the excavated material to slide over the chutes 10 and 8 and to be deposited near the foot of the mast.

Having thus described the invention, what is claimed as new, is:—

1. In a machine of the class described, a mast comprising a pair of uprights and a plurality of steps connecting the same, a chute supported adjustably on one of the steps, a dipper tiltably connected with the chute, means for tilting the dipper, and

means for raising and lowering the free end of the chute.

2. In a machine of the class described, a mast having a plurality of steps, a chute provided on its underside with a plurality of cleats, said chute being supported adjustably on one of the steps, a second chute slidably connected with the first chute, a stirrup supporting the free end of the slid- 35 able chute, a winding drum, a suitably guided flexible member connecting the wind- 40 ing drum with the stirrup, a dipper tiltably connected with the front end of the slidable chute, and means for tilting the dipper in- 45 dependently of the hoisting means for adjusting the chute.

3. In a machine of the class described, a mast having a plurality of steps, a chute supported adjustably with respect to one of the steps, said chute having forwardly ex- 50 tends arms, a dipper pivotally connected with said arms, said dipper consisting of a trough having a scoop at one end and an arm at the opposite end, said trough being 55 adapted to discharge into the chute, means for tilting the dipper, and means for rais- 60 ing and lowering the free end of the chute.

In testimony whereof I affix my signature in presence of two witnesses.

ARTHUR STEINBRECKER.
